UNITED STATES PATENT OFFICE

OSCAR A. ST. CLAIR AND EDGAR L. TENNEY, OF CHICAGO, ILLINOIS, ASSIGNEES, BY MESNE ASSIGNMENTS, TO CERTAIN-TEED PRODUCTS CORPORATION, A CORPORATION OF MARYLAND

PLASTER-BOARD-HANDLING APPARATUS

Application filed July 31, 1925. Serial No. 47,294.

This invention relates to apparatus for handling and transferring materials such, for example, as freshly formed sections of plaster board. Among other objects, the invention aims to provide an improved machine of this character which will efficiently and rapidly handle the materials for which it is designed with a minimum of manual labor and attention.

10 The nature of the invention may be readily understood by reference to one illustrative apparatus embodying the invention and shown in the accompanying drawings.

In said drawings:

15 Fig. 1 is a plan view of the apparatus, somewhat diagrammatic in character.

Fig. 2 is a sectional elevation of the apparatus, also somewhat diagrammatic in character.

20 Fig. 3 is a plan view of a portion of the transfer mechanism.

Fig. 4 is a plan view of the other portion of the transfer and the adjacent portion of the distributing mechanism.

25 Fig. 5 is a side elevation of the transfer.

Fig. 6 is an end view of the transfer and associated apparatus viewed from a plane corresponding to 6-6 of Fig. 5.

30 Fig. 7 is a detail view of a portion of the transfer operating mechanism.

Fig. 8 is a detail view taken on line 8-8 of Fig. 7.

Fig. 9 is a plan view of the hydraulic control.

35 Fig. 10 is a side elevation of the hydraulic control.

Fig. 11 is an enlarged vertical section taken on line 11-11 of Fig. 5.

40 Fig. 12 is an enlarged horizontal section taken on line 12-12 of Fig. 5.

Fig. 13 is a view of the control mechanism for the feed rolls of the distributing mechanism.

45 Fig. 14 is an elevation of the clutch, and other mechanism for controlling the distributing mechanism.

Fig. 14^a is a sectional view of elevator clutch mechanism in non-operating position.

50 Fig. 15 is an elevation of details of the feed

roll operating mechanism viewed from a position at right angles to that of Fig. 14.

Fig. 16 is a plan view of the mechanism shown in Fig. 15 and also details of the elevator control mechanism.

55 Fig. 17 is a detail of the cam mechanism for operating the ratchet rolls of the elevator.

Fig. 18 is a sectional view of the elevator feed roll clutch mechanism.

Fig. 19 is a cross section taken on line 19-19 of Fig. 18.

The illustrative apparatus is arranged, in this instance, for the distribution of materials, plaster board for example, to kilns or drying rooms, or to other apparatus for further treatment.

65 Plaster board is usually prepared in a continuous web by well known machines adapted for that purpose. The board thus formed then usually requires treatment, by drying for example, to remove excess moisture, and for this purpose it is usually cut into sheets of various lengths for convenience in handling.

70 In the present apparatus, the plaster board is received in suitable lengths from the plaster board machine and is mechanically delivered to or introduced into drying apparatus. In the present instance the drying apparatus comprises a plurality of conveyors or the like arranged at different levels, each arranged to receive the plaster board and conduct it through the drying chamber.

75 In the present arrangement, the product in the form of separate sheets of plaster board is delivered, after the plaster board has set sufficiently to render the boards capable of being handled, at the end of conveying means represented by the roll conveyor 1. Preferably some means, such as a higher speed conveyor (not shown), is provided for separating the various sections of board by a short distance prior to delivery so that there will be an interval between successive deliveries of boards at the end of the conveyor.

80 From the conveyor 1, the boards 2 are delivered to drying apparatus for driving off excess moisture, such apparatus being typified by a suitably inclosed conveying means 14.

in the form of a plurality of levels or "decks" of driven rollers (see Fig. 2). For convenience in arrangement and conservation of space, the drying apparatus is advantageously located beneath the conveyor of the board machine and carries the boards in the reverse direction, that is, in the direction opposite to that in which they are carried by the conveyor of the board machine. The speed of the conveyors of the drying apparatus is adjusted in accordance with the capacity of the apparatus, namely, the rate at which the apparatus will dry the boards to the proper condition. To provide a drying apparatus of adequate capacity, without objectionably increasing the length of the drying apparatus, the conveying means of the apparatus is advantageously made of a width to carry side by side a plurality of boards. For example, if the conveyors be arranged to carry two boards side by side, the lineal speed of the drying conveyors need be only half that necessary where the conveyors are of a width to carry only a single board. Thus, still greater capacity for the dryer, or a reduction in its length, or a reduction in the speed of its conveyors, may be effected by designing the conveyors of the dryer to receive a still greater number of boards side by side and to carry them simultaneously through the dryer.

To permit the use of a dryer of this character, means typified by an accumulating transfer 5 is provided for arranging the boards so that they may be introduced into the dryer side by side.

In the illustrative apparatus the accumulating transfer 5 comprises a conveyor table 6 having conveying means in the form of driven feed rollers 7 for receiving the board from the rollers 3 of the board machine conveyor. Suitably spaced between the driven rollers 7 are idle rollers 8 mounted appropriately in the transfer table to support the board as it is received.

Motor 9 supported on base 10 and having speed reducing means 11, represents means for driving feed rolls 7. The motor drives counter-shaft 12 through chain 13 and suitable sprockets, from which shaft the roller drive 15 is driven by chain 14. The roller shafts 18, 19 and 20 are driven from shaft 15 through bevel gears 16, 17 (Fig. 3) and chains 21 and 22 connecting shafts 19 and 20 with shaft 18.

The transfer table is made of a width to hold a plurality (in this instance two) of boards side by side. They are shifted laterally by periodically operating shifting means in the form of short rolls 26 and 27 located between rolls 7 and 8 and supported by brackets 25 with their axes at right angles thereto. Such rolls are brought into operative position to shift a board laterally, in this instance, by periodically raising them slightly above

the surface of rolls 7 and 8, and for this purpose such rolls are supported on a vertically movable frame 23 slidably mounted between guides 24 in frame of transfer table 6 (Figs. 7 and 8).

Rolls 26 are driven from shaft 12 by sprocket shaft 31, and chains 30^a, 33 and 34 which run over appropriate sprockets. Shaft 31 is supported in appropriate brackets 32. Rolls 27 in this instance are simply idle supporting rolls. The proportion of driven and idle rolls obviously may be changed to suit the requirements of the product. In the present arrangement the rolls 26 are arranged to be driven only periodically when their supporting frame is raised to operative or shifting position, means for this purpose being represented by clutch 28 having a driving portion 29 and longitudinally slidably driven portion 30, (Fig. 7). The clutch is engaged and released at appropriate times by yoke member 37 slidably mounted upon a square shaft 38 and actuated by link 36 connected at its other end with a rock arm 39^b. In the present arrangement, the rock arm 39^b is oscillated by control lever 31^b (Fig. 5) through rock arm 39 secured at one end to rock shaft 40 and at its other end to the link 35 which connects it with the pivoted lever 31^b. Thus oscillation of the lever 31^b engages or releases the clutch to rotate the cross rolls 26.

The shifting conveyor frame 23 is carried by rocking arms 41 (having supporting anti-friction rollers 41^a) typifying means for raising and lowering the shifting conveyor at appropriate intervals. The frame 23 is slightly over-balanced, so that it tends to remain in raised position, by weights 42 connected with the rocking arms 41 (Figs. 5 and 8). The rocking arms 41 are, in this instance, in the form of bell cranks, the opposite arms of which are connected with link 35, whereby the shifting conveyor rolls may be raised simultaneously with their actuation by their driving means, upon the operation of control lever 31^b,—thus conveniently co-ordinating the roller drive control with the vertical movements of the roller frame.

Thus, after a board is received upon the transfer table, it is shifted laterally (upon movement of lever 31^b) by the cross rolls 26, its lateral movement being arrested by lowering of the rolls. By appropriate design, as many boards may be accumulated laterally or side by side as the size of the transfer table will permit. The last board of each accumulation need not be shifted but may remain on the transfer table in alignment with the board machine conveyor.

Following the lateral shifting, the board is fed beyond the opposite or discharge end of the transfer table by the feed rollers 7. A stop 43 across the discharge end of the transfer table prevents the premature discharge

of any boards from the transfer table. The stop is lowered into inoperative position by an operating lever 47 (conveniently adjacent the control lever 31^b) connected to rock shaft 45 to which is also connected a rock arm 46 (Figs. 5 and 11), which reciprocates the stop operating lever 44. The longitudinal movement of the stop operating lever 44, in this instance, simply swings the links 44^a, which support the stop 43, into an inclined position, thus lowering the stop below the surface of the transfer table. After the boards have been discharged from the transfer, the stop is again raised by throwing lever 47 in the opposite direction.

Depending upon the arrangement and character of the drying or other apparatus the boards may be delivered from the transfer either directly to the drying apparatus or to distributing means which deliver the boards to the drying apparatus. In the present machine the boards are delivered to a distributing apparatus in the form of a vertically operating elevator 48 (the dryer conveyors being vertically spaced) which receives the boards and delivers them to the drying apparatus. The first board of each pair is, in this instance, delivered from the transfer to the distributing apparatus as soon as it has been shifted laterally without waiting until the succeeding board is fully on the transfer (the distributing elevator is, of course, in position to receive the board). Where more than two boards are placed side by side, the shifting and delivering thereof to the distributing device may be effected by appropriate design of the transfer operating mechanism.

Because the travel of the boards in the dryer is in a direction opposite to that in which they travel to the distributing device, the latter also represents, in this instance, means for reversing the travel of the boards. In general, the distributing device is designed to make the character of distribution required by the apparatus to which it is delivered. For example, in the present instance, the drying apparatus comprises a plurality of superposed conveyors which involve a vertical distribution of the product. Means for effecting such vertical distribution is typified by the vertically operating hydraulic elevator 48^a which supports and vertically moves the distributing device 48. In the present arrangement, the elevating mechanism is carried in a pit 50^a. Control means in the form of a hydraulic control valve 49 serves to actuate such mechanism to raise and lower the distributing device 48 and to stop it at proper levels to discharge the product into the drying apparatus. Hydraulic pressure for the elevator may be supplied by any appropriate apparatus, typical apparatus for this purpose being illustrated diagrammatically in Fig. 1.

The valve 49 is controlled by lever 50 having, in this instance, three control positions,

namely, one for raising the distributing device, another for stopping it at any desired position, and the third for lowering the distributing device (Fig. 10).

In addition to manual control means, the distributing elevator is provided with automatic control means, in this instance acting in conjunction with the control lever 50. Such means automatically lowers the distributing elevator to, and arrests it at, the proper level for discharging the product. In the illustrative apparatus, the control means is also conveniently provided with selecting means for controlling the sequence in which the product is delivered to the various levels of conveyors of the drying apparatus, such sequence, in this instance, being successively from the top to the bottom of the conveyor and thence again to the top.

Such automatic control means is typified in the present apparatus, by control stops 61 and 61^a projecting from the frame of the distributing device 48 (Fig. 11) and co-operating control levers or cams 55 and 55^a, the former designed to be selectively operated according to the sequence of distribution to the various levels of the drying apparatus. A cam or lever 62 is provided for each of the levels (in this instance four) of the drying apparatus.

Cams 62, which in this instance are initially operated upon the lowering of the elevator, are suitably pivoted by shafts 63 arranged appropriately relative to each of the levels of the conveyors of the drying apparatus. One end of each cam 62, in this instance the upper end, (as shown in Fig. 12) lies in the path of stop 61 on the elevator (see Figs. 11 and 12) and engagement therewith serves to rotate cam 62 and shaft 63 to raise arm 64. Arm 64 has a yoke shaped terminal which embraces control rod 66 and raises the same through an appropriate collar 65 (see Figs. 11 and 12). The supports for shaft 63 are arranged to permit cam 62 to be moved to the right (as shown in Fig. 12) in which position it is out of the path of stops 61 and 61^a and is not actuated thereby. Appropriate devices, hereinafter described, are provided for holding certain cams 62 in inoperative position, thus only the particular cam 62 which projects (as shown in Fig. 12) beyond its inoperative position, lies in the path of the operating stop 61.

Rod 66 is operatively connected with the hydraulic valve 49 through bell crank lever 67 (Fig. 5) and rod 68, the end of the latter being connected with rock arm 68^a carrying a trip stop in the form of an adjustable set screw 70, which trips lever 50 to return it to "stop" position. The tripping mechanism is, in this instance, typified by latch 51, pivoted at 52 engaging a stud 53 projecting from the lower end of lever 50. The latch 51 serves momentarily to retain the operating lever in "lowering" position where it is shifted by the

operator when it is desired to lower the elevator. Upon movement of rod 68 (to the left as shown in Fig. 10) the tripping screw 70, raising latch 51, permits the spring 71 to restore lever 5 to "stop" position, in which position it is retained by the stop surface 69 provided on rock arm 68^a and which has been moved, in the meanwhile, into the path of the stud 53 and is engaged thereby. (See Fig. 10.)

As soon as the elevator is stopped at the proper level, automatic means actuate the distributing device to discharge the product. Such product is received by conveyors, in the form of rolls 57 supported in conveyor frames 56 slightly inclined away from the elevator. These conveyors lead to the appropriate conveyor in the drying apparatus. Certain rolls 58 of the conveyors are driven by belts 60 from driven shaft 20 (Fig. 5).

The distributor discharging means are typified by driven rolls 92 supported in the distributor frame and arranged to move the product in the appropriate direction, depending upon the relative location of the drying apparatus. In the present apparatus, these rolls are arranged to feed the product in the direction from which it was received, thereby reversing its travel. For different relative locations of the dryer suitable changes in the arrangement of the conveyor of the distributing device may be made.

Power to drive rolls 92, is provided by motor 87 through gear 86^a on shaft 86 supported in suitable brackets below the frame of the distributing device. (Figs. 4 and 15.) The shaft 86 delivers power to sprocket 87^a from which it is transferred by chain 88 to sprocket 89, in this instance on shaft of one of the rolls 92. From such shaft power is distributed to other rolls 92 desired to be driven by chain 90 which runs over sprockets 91 on the various roll shafts. The number of driven rolls 92 may be varied simply by adding or removing sprockets 91, the other rolls being simply idle supporting rolls.

The roll drive in the present machine, is only in one direction, the rolls being provided with clutches in the form of co-operating ratchet dog and ratchet plate 101 and 102, which permit rolls 92 to be rotated in the reverse direction, independently of their drive. Thus, the rolls are free to rotate when the board is fed thereon from the transfer mechanism. Co-operating with the roll clutches are means which periodically engage the roll clutches for driving the rolls at the desired times to discharge the product from the distributing elevator, such means being typified in the clutch operating rods 100 which may be actuated to move ratchet dog 101 into driving engagement with ratchet 102, the clutch being normally held "released" by spring 103 (Fig. 18). Pivoted cams 98 represent means for actuating the clutch rods 100, such cams,

in this instance, being simultaneously operated by connecting rod 97 which is operated by sliding rod 95 through link 96.

Rod 95 is reciprocated at the proper time to engage the roll clutches by automatic means in the form of a pivoted trip 72 (Fig. 14) carried on the frame of the distributing device and which engages one of a series of cams 55 located in the path of trip 72 at the appropriate level. The upward movement thus given to trip 72 is communicated, in this instance, to slide 95 by link 75 connected at one end to rocking arm 74 on the trip rock shaft 73, and at its other end to a rock arm 76, the latter having a pin 93 operating in a slot in bracket 94 on slide 95.

The cams 55 are selectively placed in the path of trip 72 by periodic rotation of shaft 54 on which said cams are mounted in angularly spaced relation (see Fig. 4). The angular arrangement of the respective cams on shaft 54 conveniently corresponds with the sequence in which the distributing device delivers the product to the respective conveyors of the dryer. This arrangement of cams 55 is advantageously coordinated with the operation of the cams 62, that is, cams 62 and 55 at a given level are arranged in operative relation to operate at the same cycle of movement of the elevator. In the present machine, a pair of cams 55 is provided for each level, thus requiring only half a complete revolution of shaft 54 to bring another cam, at a given level, into operative position.

The elevator having been brought to rest at a given level through the co-operation of stop 61 and the operative cam 62, the raising of trip 72, (which advantageously occurs substantially simultaneously with the stopping of the elevator at that level) engages the roll drive, whereupon the rolls 92 feed the product from the distributor and delivers the same to the receiving rolls 56 and 57 of the driven dryer conveyor.

Appropriate means (either manually or automatically operated) are provided for arresting the rotation of rolls 92 and returning the distributor to receiving position upon the delivery of the product therefrom to a dryer conveyor. Such means are typified herein by the lever 104 which, through engagement with pin 106 on link 75 serves to move slide 95 in the reverse direction, thus releasing the roll clutches, and restores trip 72 to its normal or substantially horizontal position. The lever 104 is in this instance manually operated by a connecting element such as rod 105 (Fig. 2) which extends to a point where it may conveniently be operated by the machine operator. In the present machine, the operator stands on platform 111 where he is in convenient reach of all of the controls. The outward or downward movement of trip 72 resulting from the operation of lever 104, serves, in the illustrative ap-

paratus, to move the preceding active cam 62 into inoperative position by sliding shaft 63 longitudinally until latch 107 snaps over shaft collar 108, thereby holding this cam in inoperative position, out of the path of stop 61 on the next descent of the elevator. The foregoing movement of cam 62, beyond control of stop 61, permits rod 66 (previously held in raised position by depression of cam 62 by stop 61) to fall under its weight and that of associated parts. The reverse movement of rod 66 moves rod 68 to the right (as shown in Fig. 10) thus raising the stop surface 69 until it clears stud 53, whereupon lever 50 is moved to "raise" position by spring 71 and the elevator rises.

The adjustment or setting of cams 55 is effected, in this instance, by the elevator upon its upward movement, means for this purpose being typified in the co-acting stop 61^a on the elevator and the pawl 55^a which is raised thereby to rotate shaft 54, (Fig. 11). Pawl 55^a is pivoted about shaft 54^c and carries a ratchet spring 55^b engaging a ratchet 55^c on shaft 54^c to rotate the latter and, through meshing spiral gears 54^b, to rotate shaft 54 a portion of a turn. The movement of pawl 55^a under the action of stud 61^a is illustrated in dotted lines in Fig. 11. This fractional rotation of shaft 54 brings the next cam 55 in sequence into operative position relative to trip 72.

The same rotation of shaft 54 is employed in the illustrative apparatus to set cams 54^a, one of these being provided for each level of the dryer. Such cams are secured to shaft 54 in angularly spaced relation and adjusted to cooperate with other control mechanisms which are actuated at a given level. Cams 54^a (also being provided in pairs in this instance), serve to release cams 62 upon successive operations to place the proper cam in operative position. This is effected by raising latch 107, through engagement of a cam 54^a with the releasing button 109, (Fig. 12), to release shaft 63 which, under the pressure of its spring, moves the cam 62 into operative position. As stated above, the particular cam thus released is that for the next stage or level to receive the product from the distributing elevator. Thus, when the elevator rises, the appropriate cam 54^a sets the corresponding cam 62 to stop the elevator at the proper level on its next downward movement.

When the elevator has completed one series of distributions to all conveyors from the top to bottom, its return movement again sets the uppermost cam 62 to stop the elevator at the upper dryer level.

Arbitrary variation of the sequence of distributions by the elevator may be effected by manual rotation of shaft 54 through shaft 54^c. For this purpose a hand lever 110 is

provided on shaft 54^c and located for convenient manipulation by the operator.

If desired, the driving mechanism for the distributor rolls 92 may be provided with a master clutch which releases the driving sprockets 87^a, 89 and 91 and their co-operating chains 88 and 90, whenever the individual clutches on the rolls 92 are released. For this purpose a clutch typified by clutch plate 83, pawls 82 and ratchet 85, is provided for shaft 86. Clutch plate 83 is secured to sleeve 83^a free on shaft 86 and carries spring 84^b which normally holds pawls 82 in engagement with ratchet 85 (Figs. 14 and 15). Drive sprocket 87^a is, in this instance, secured to and driven by, clutch sleeve 83^a. The clutch may be disengaged by a pair of clutch pins 81, which hold the pawls out of engagement with the ratchet. Such pins are normally held in engagement with the pawls by spring 84^b. The clutch is engaged, by withdrawal of pins 81, by devices controlled by the trip link 75. Such devices are represented herein by shaft 77, connected with the rock arm 76, and carrying a side face rocking cam 78 which engages roller 79 on clutch pin slide 80 to move pins 81 out to release the pawls (Figs. 14 and 15). Such operation takes place simultaneously with the engagement of the individual clutches for rolls 92.

Obviously the present invention is not restricted to the details of the illustrative apparatus herein shown and described. Moreover, it is not indispensable that all the features of the invention be used conjointly, since they may be employed advantageously in various combinations and sub-combinations.

Having described one embodiment of our invention, we claim:

1. In apparatus for handling plaster board sections, the combination comprising a conveyor, an elevator, and means for transferring the sections from the conveyor and delivering them to the elevator in selective angular directions in a horizontal plane.

2. In apparatus for handling plaster board sections the combination comprising an elevator for receiving board sections, unloading means for transferring the sections from the elevator to a drying room, means for actuating the unloading means, and means for automatically operating the actuating means when the elevator is at rest.

3. In apparatus for handling plaster board comprising in combination a conveyor supplying boards from board forming means, drying apparatus having conveying means travelling in a direction opposite that of said conveyor, and means for changing the direction of travel of said boards and delivering them to the dryer conveying means.

4. In apparatus for handling plaster board sections, the combination comprising a con-

veyor, a transfer adapted to receive the plaster board sections, from said conveyor, an elevator, means for transferring the plaster board sections from the conveyor and delivering them to the elevator, and means for lowering the elevator for transferring the plaster board from the elevator to drying apparatus.

5 5. In a plaster board handling apparatus, a dryer comprising decks at different levels, an elevator, mechanically operated means adjacent the dryer and adapted to cooperate with the elevator for automatically stopping the elevator successively at different decks 10 at each descent.

15 6. In plaster board handling apparatus, receiving means comprising in combination decks at different levels, an elevator, means adjacent the decks and adapted to cooperate 20 with the elevator for automatically stopping the descent of the elevator at a predetermined deck, conveying rolls on said elevator and automatic means to actuate said rolls periodically with the stopping of the elevator.

25 7. The method of transferring freshly made plaster board sections from a forming machine to a drying apparatus, consisting in feeding plaster board sections lengthwise and crosswise in one plane and moving the 30 sections to another plane from whence same are delivered to a dryer.

8. The method of handling plaster board sections which consists of feeding a section, feeding another section in the same plane and 35 parallel to the first mentioned section, lowering the two sections to a lower plane and reversing their direction of travel.

9. The method of feeding plaster board 40 sections to a transfer, moving the sections laterally on the transfer to arrange same in a row, feeding the row of sections from the transfer to an elevator, actuating the elevator to a predetermined plane and feeding the plaster board section therefrom.

45 10. The method of feeding a plaster board section to a transfer, feeding another plaster board section to the transfer, feeding both plaster board sections at the same time to an elevator, lowering the elevator to a lower 50 plane and feeding the plaster board sections therefrom to a dryer.

11. In an apparatus for handling board sections, the combination comprising an accumulating mechanism and a vertically movable receiver, said mechanism being provided 55 with means for arranging the sections in a row and feeding same to said receiver.

12. The method of feeding material to a transfer, moving the material in selective angular directions on the transfer, feeding the material to an elevator, and actuating the elevator to another level in a path perpendicular to the horizontal plane of the transfer.

65 13. In apparatus for handling plaster

board sections, the combination comprising a transfer to receive the sections, rollers for feeding the sections lengthwise of the transfer, a stop adjacent the discharge end of the transfer, and means for moving the stop 70 away from the path of the sections.

14. In a plaster board handling apparatus a dryer arranged to accommodate board sections at various levels, an accumulating transfer and an elevator, and means for automatically delivering sections accumulated on the transfer from the elevator to predetermined levels of the dryer.

75 15. In a plaster board handling apparatus, in combination, an accumulator arranged to accommodate board sections at various levels, a dryer and an elevator, means for transferring accumulated boards from the accumulator to the elevator, means for automatically delivering board sections from the elevator to successive levels of the dryer and means for automatically returning the elevator to the level of the accumulator preparatory to a repetition of the cycle.

80 In testimony whereof we affix our signatures.

OSCAR A. ST. CLAIR.
EDGAR L. TENNEY.
